UNITED STATES PATENT OFFICE.

PALMER COX, OF NEW YORK, N. Y.

DESIGN FOR A BOOK-COVER.

SPECIFICATION forming part of Design No. 24,045, dated February 19, 1895.

Application filed January 19, 1895. Serial No. 535,564. Term of patent 14 years.

To all whom it may concern:

Be it known that I, PALMER COX, a citizen of the United States, residing in the city, county, and State of New York, have invented 5 and produced a new and original Design for Book-Covers, of which the following is a specification.

The leading feature of my design consists in a book-cover ornamented substantially as 10 represented in the accompanying drawings, forming part thereof, which show a book-cover embodying my design, the front thereof being shown in Figure 1, and the back in Fig. 2.

In the drawings (Fig. 1) A represents a 15 house with an arch B from which peers a brownie-like face, and which is surmounted by series of oriel windows a a a a in which brownie-like faces c c c c appear. On either side of the arch is a window d d in which a brownie-like face e e appears.

In Fig. 2, which represents the back of the book, a' is a scroll set up in a landscape and flanked by trees or shrubs b' b' and by brownie-like figures c' c', and having brownie-like figures d' d' in the foreground.

What I claim is—

The design for a book-cover, substantially as herein shown and described.

PALMER COX.
